DESIGN FOR AN UPRIGHT PIANO

Henry R. Heller, Larchmont, N. Y., assignor to Winter & Co., a corporation of New York

Application May 28, 1935, Serial No. 57,055

Term of patent 7 years

To all whom it may concern:

Be it known that I, Henry R. Heller, a citizen of the United States and a resident of Larchmont, in the county of Westchester and State of New York, have invented a new, original, and ornamental Design for Upright Pianos, of which the following is a specification, reference being had to the accompanying drawing, forming part thereof.

The drawing is a perspective view of an upright piano embodying my new design.

I claim:

The ornamental design for an upright piano, substantially as shown.

HENRY R. HELLER.
